UNITED STATES PATENT OFFICE.

WILLIAM C. HOMAN, OF MERIDEN, CONNECTICUT, ASSIGNOR TO EDWARD MILLER & COMPANY, OF MERIDEN, CONNECTICUT, A CORPORATION OF CONNECTICUT.

GLOBE AND SHADE HOLDER.

1,074,719

Specification of Letters Patent.

Patented Oct. 7, 1913.

Application filed November 11, 1912. Serial No. 730,545.

To all whom it may concern:

Be it known that I, WILLIAM C. HOMAN, a citizen of the United States, residing at Meriden, New Haven county, State of Connecticut, have invented certain new and useful Improvements in Globe and Shade Holders, of which the following is a full, clear, and exact description.

This invention relates to an improved construction of globe and shade holder of the type more particularly used in connection with the so-called inverted burners.

The present invention is an improvement over the structure shown in my Patent No. 1,029,298, and is described in detail in the following specification and illustrated in the accompanying drawings forming part thereof and illustrating a preferable embodiment of the invention.

20 In these drawings: Figure 1 is a bottom plan view of the globe support, the burner tube being detached therefrom. Fig. 2 is a vertical section through said globe support, and Fig. 3 is a view in elevation illustrating my improved construction.

Referring to the drawings by numerals, 1 indicates the main body portion of the globe holder, to the top 2 of which the burner tube is secured, said tube extending down- 30 wardly within the holder and globe as usual. At its lower edge, the main body portion 1 is formed with a depending annular flange 3 having preferably an internally channeled portion extending entirely around said flange.

The holding device comprises a one-piece spring wire bent in the middle to form a U-shaped portion 4 which projects through a slot 5 in the annular flange 3. Extending 40 in opposite directions from the U-shaped portion of this wire retainer, are arms 6 and 7, each of which is of greater length than a semi-circle so that the two ends of the wire will overlap. The extreme ends of the wire 45 are offset as illustrated to provide operating handles 8 and 9.

10 designates an elongated slot in the annular flange 3 opposite the slot 5 therein, said slot 10 preferably being widest at its 50 middle portion, with the two ends thereof slightly out of line.

A bar 11 forming an abutment member is provided adjacent the slotted portion 5 of the flange 3, this bar, which may be in the 55 form of a metal clip, extending transversely

of said slot 5 and having its ends inserted through apertures 12 above and below said slot and clenched against the inner face of the flange 3 to securely hold the bar to said flange. This bar or abutment is inserted 60 subsequent to the projection of the U-shaped portion of the wire through the slot 5 in the annular flange of the shade holder so that it will retain said U-shaped projection in engagement with said annular flange.

The spring wire retainer is normally contracted so that it forms a ring member of appreciably less diameter than the interior diameter of the holder. By gripping the handle ends 8 and 9 with the thumb and forefinger and pressing them together, the side arms 6 and 7 of the retainer will be extended laterally into the channel around the inner side of the flange 3, thus affording sufficient clearance to permit the flanged upper end of a globe to be inserted within the holder to a position above the arms 6 and 7. Upon releasing the handle ends 8 and 9, the wire retainer contracts, bringing the side arms 6 and 7 into gripping contact 75 with the edge of the globe beneath its end flange so as to securely hold the latter in place within the holder.

In my prior patent hereinbefore referred to, No. 1,029,298, I retained the U-shaped projection of the wire retainer in engagement with the flange of the shade holder by forming the slot through which said projection passed with a centrally restricted portion or hour-glass contraction which was 80 formed by bending the edges of the annular flange of the shade holder inwardly after the U-shaped projection of the wire retainer had been inserted through said slot. I find, however, that my present construction is more 85 effective in retaining the projecting end of the retainer in engagement with the flange of the shade holder, inasmuch as it provides a more positive and stronger retaining abutment and is less liable to become bent or 90 broken so as to become inoperative.

What I claim, therefore, and desire to secure by Letters Patent is:

In a globe or shade holder, an annular sheet metal flange, a ring-like wire shade 105 retaining element having a U-shaped projection, said flange having a slot formed therein through which said projection extends, a retaining bar distinct from said flange extending transversely of the slot 110

therein, and between said flange and the end of said U-shaped projection, said bar being fixedly attached to said flange to thereby retain said projection against disengagement from said flange, said ring-like element having its ends offset to form operating handles, and said annular flange having

a second elongated slot therein through which said handles pass to the outside of the flange.

WILLIAM C. HOMAN.
